GRINDING MACHINE

Charles Louis Godar, Paris, France, assignor to Etude
et Réalisation d'Omnis Precision "E.R.O.P." C. L.
Godar, Courbevoie, France, a corporation of France

Filed Apr. 13, 1961, Ser. No. 64,721

Term of patent 14 years

(Cl. D37—1)

FIG. 1

FIG. 2

FIGURE 1 is a front perspective view of a grinding machine showing my new design;

FIGURE 2 is a top plan view thereof;

FIGURE 3 is a rear elevational view thereof; and

FIGURE 4 is a side elevational view taken from the left of FIGURE 3.

I claim:

The ornamental design for a grinding machine, as shown.
